SHOULDER PAD.

Walter Riedler and Berthold Mechur, New York,
N. Y., assignors, by mesne assignments, to
Perma-Fit Shoulder Pad Co., Inc., New York,
N. Y., a corporation of New York

Application March 5, 1949, Serial No. 79,825

5 Claims. (Cl. 2—268)

1

This invention relates to a structurally and functionally improved shoulder pad for garments and especially ladies' garments and dresses in which no linings may be present.

It is an object of the invention to furnish a unit of this type which will be complete in itself and may accordingly be applied to impart to the shoulder portion of a garment, the desired finished contour without it being necessary to employ a sleeve head or any other auxiliary or supplementary structure to complete the contouring of the same at the shoulder.

A further object is that of furnishing a shoulder pad which will not incorporate, in its underface, an undesired and slack structure. Rather the several layers of the unit will be intimately associated with each other in a manner such that relative movements will not occur.

An additional object is that of providing a device of this type which may be economically manufactured by quantity production methods and by relatively unskilled labor; the pad being capable of ready application to a garment and maintaining its shape as well as the shape of the garment even when subjected to repeated cleaning operations.

With these and other objects in mind, reference is had to the attached sheet of drawings illustrating one practical embodiment of the invention, and in which:

Fig. 1 is a perspective view of the improved shoulder pad;

Fig. 2 is a sectional side view thereof taken along the lines 2—2 and in the direction of the arrows as indicated in Fig. 1;

Fig. 3 is a transverse sectional view taken along the lines 3—3 and in the direction of the arrows as indicated in Fig. 2;

Fig. 4 shows the several units or layers which form the pad separated from each other;

Fig. 5 is a plan view of an assembly prior to the shaping operation; and

Fig. 6 is a transverse sectional view taken along the lines 6—6 and in the direction of the arrows as indicated in Fig. 5.

Attention being primarily invited to Fig. 4, it will be seen that the pad preferably embraces merely three major portions. These include the form-imparting element 10, a rigidifying element or sheet 11 and a covering layer 12. Elements 10 and 11 may be formed of any desired fiber such as wood, wool, cotton, rayon, etc. The fibers of element 11 may be relatively compacted to furnish a comparatively stiff or rigid sheet. The fibers of element 10 are comparatively loose so

2

as to provide a yielding body portion. The covering 12 may conveniently be formed of rayon or similar cloth and be entirely flexible. It is preferably, however, cut on the bias so that its lines of weave extend angularly both with respect to the longitudinal and transverse axes of the garment.

Element 11 has what might be termed a notched base edge 13; its opposite edges 14 being somewhat curved. The area of element 11 is slightly in excess of the maximum area defined by the edges of element 10, excepting only for the notch 13. The outlines may be substantially identical and again excepting only for the notched portion of element 11. The edge of element 10 is bevelled or reduced as indicated at 15. Again it is preferred that this beveling be not extended through to the lower edge of element 10. Rather it should terminate short of same to provide a vertical edge portion 16.

In providing the unit, the material sheet 12 is placed upon a supporting surface. The rigidifying sheet or element 11 is superposed on the sheet 12 and to one side of the center of the seam as indicated in dash and dot lines on the face of sheet 12 in Fig. 4. In turn superposed upon element 11 is element 10. Thereupon, sheet 12 is folded upon itself as in Figs. 5 and 6. The assembly is maintained in position preferably by employing a staple 17 or any equivalent unit extending through enough of the layers to anchor them. At this time it will be understood that while in certain instances the adjacent faces of elements 10 and 11 might have applied to them a suitable adhesive and other faces of the assembly might be likewise treated, it has been found in practice that this coating of the parts is unnecessary, and in certain instances, objectionable.

Therefore, ordinarily, the assembly as illustrated in Figs. 5 and 6 will be directly transferred to an apparatus which includes cooperating molds between which the assembly is disposed. These molds will be capable of exerting substantial pressure and heat. They will be contoured so that the initially substantially straight edge of element 10 will have a curvature imparted to it as indicated at 18 in Fig. 2. The element 10, thus subjected to molding, has its straight edge impressed into the cut-away notch 13 of the stiffening element 11. The edge of the padding material, which is pressed into the cut-away notch provides, at least in part, the curvature 18 of the padding element 10. This curved edge portion is, of course, in addition to the transverse curvature which is imparted to the several com-

ponents of the pad by the molding and as shown in Figs. 1, 2, and 3. The amount of material of the padding element 10 which is molded into the cut-away notch 13 is tapered in accordance with the curved shape of the cut-away notch 13. A lip 21 is formed by the material which is turned over the notched base edge 13 of the stiffening element 11. The center of the lip 21 embodies the greatest amount of material as it fits into the cut-away portion of the element 11. The quantity of material of the lip 21 which fits into the notch 13 tapers off from the center toward the sides as a consequence of the narrowing of the cut-away area.

The shoulder pad has an outer peripheral edge 15 formed by the fold of the covering layer 12. This outer peripheral edge with its transverse curvature is designed to fit the shoulder pad to the arm hole of a garment. The shoulder pad when fitted in a garment is fixed with its inner apex tilted upward as it follows the normal shoulder line of the garment and the wearer. As a consequence of this tilting of the shoulder pad, the arm hole of the garment described a plane which is not perpendicular to the axis of the transverse curvature of the shoulder pad. Line A—A shows the axis of the transverse curvature of the shoulder pad. Line B—B is a perpendicular to the axis A—A. The outer peripheral edge of the shoulder pad is non-30 perpendicular to the axis A—A.

The lip 21 is formed into the cut-away portion of the notch 13. The middle of the shoulder pad is curved inward and conforms to the arm hole of a garment because of the greater amount of the padding element 10 folded into the cut-away portion at the center of the pad. Thus, the outer peripheral edge of the shoulder pad fits around the arm hole of a garment while the inner apex of the pad fits to the shoulder portion of the garment.

With the pad removed from the mold, it will now be applied to, for example, a sewing machine which will incorporate two lines of stitches 19 in the pad. These rows of stitches will pass through the covering sheet 12 and the adjacent edge portions of elements 10 and 11. They will obviously serve to permanently retain the several parts of the pad against movement. Thereafter, the staple or other securing element may be removed if desired.

Simultaneously with the stitching operation, the exposed edges of sheet 12 may be notched or "pinked" in order to prevent an unravelling of the same. This has been indicated at 20.

With layer 12 cut on the bias, it is found that with the establishment of the rows of stitches, parts of the pad are placed under a slight degree of tension. No "bagging" on the underface of the pad will occur; this being partially attributable to the fact that the body of element 10 extends somewhat downwardly within and beyond the edge of notch 13 incident to the molding operation and as indicated in Fig. 2. As a consequence of this construction, no central line or lines of stitching are necessary and a more desirably contoured pad is provided.

As especially indicated in Fig. 3, the pad when viewed from the edges presents a body which is preferably shorter in front and longer in back. In other words, it is frequently desirable in order to properly drape and contour a garment to have the pad extend forwardly of the shoulder only a relatively short distance although it should extend to the rear of the shoulder a greater dis-

tance. By the construction suggested in Fig. 3 this result is achieved. Also it will be understood that while in many respects it is preferred the pad include a supporting as well as a cushioning element, only a single element need, in certain instances, be employed within the covering sheet. Under other conditions a number of layers greater than that illustrated might be utilized.

10 Thus, among others, the several objects of the invention as specifically aforesaid are achieved. Obviously numerous changes in construction and rearrangement of the parts might be resorted to without departing from the spirit of the invention as defined by the claims.

We claim:

1. A shoulder pad including in combination a covering sheet of flexible material of substantially rectangular outline, a supporting element of relatively rigid material, a cushioning element of relatively resilient material, said flexible sheet being folded substantially centrally upon itself along a line extending from one to another diametrically disposed corner to envelope said elements with the supporting element disposed below said cushioning element and a concave curved edge of said rigid element presenting a recessed edge portion of said element; the adjacent body of said cushioning element being permanently distorted and maintained within such recessed edge portion.

2. A method of forming a shoulder pad which includes the utilization of an outer substantially rectangular sheet of flexible material having warp and woof threads extending on the bias and a cushioning element of relatively resilient material of substantially triangular outline and a layer of relatively rigid material of substantially triangular outline having one recessed edge, arranging said cushioning element on said rigid material, forming in a curve a portion of said cushioning element over the recessed edge of said rigid element, arranging said cushioning element and said rigid element with said recessed edge along the center line of said outer sheet, folding said outer sheet along the center line, and fastening the folded edges of said outer sheet together with said portion of said cushioning element curved over said recessed edge.

3. A shoulder pad including in combination a substantially rectangular sheet of flexible material having warp and woof threads extending on the bias, a layer of relatively rigid material providing a strengthening element, a cushioning element comprising a layer of relatively resilient material having substantially triangular outline, the outline of said strengthening element being also substantially triangular, said flexible sheet being folded upon itself to envelop such elements and being disposed in face-to-face contact with the same, said elements and said sheet being permanently curved in both longitudinal and transverse directions and the edges of the sheet being maintained in face-to-face contact to provide a permanent enclosure for said elements, a concave edge of said strengthening element providing a recess adjacent said strengthening element, and adjacent portions of the body of the resilient element extending into the said recess adjacent said strengthening element.

4. A method of forming a shoulder pad which includes the utilization of a sheet of flexible material and a cushioning element of relatively resilient material of substantially triangular outline and a layer of relatively rigid material of

substantially triangular outline having one recessed edge, arranging said cushioning element on said rigid material, arranging said cushioning element and said rigid element with said recessed edge along the center line of said outer sheet, folding said outer sheet along the center line thereof, molding said assembled elements under heat and pressure, folding a lip of said cushioning element in a tapered indentation in the recessed edge of said rigid element under said molding pressure to form the lip in a tapered shape with its greatest bulk at the center, and imparting a transverse curvature to said assembled elements including said tapered lip.

5. A shoulder pad including in combination a substantially rectangular sheet of flexible material, a layer of relatively rigid material providing a strengthening element, a cushioning element comprising a layer of relatively resilient material having a substantially triangular outline, a concave edge forming an indentation in one side of said strengthening element, the flexible sheet being folded upon itself to envelop such elements along a line determined by the outer ends of said concave edge, and a lip of said

10
